N. P. THYGESEN

HANDBALL, PUNCHBALL, AND THE LIKE

Filed Dec. 24, 1924

Fig 2.

INVENTOR:
Niels Peter Thygesen
BY: Francis E. Bayne
ATTORNEY.

UNITED STATES PATENT OFFICE.

NIELS PETER THYGESEN, OF COPENHAGEN, DENMARK.

HANDBALL, PUNCHBALL, AND THE LIKE.

Application filed December 24, 1924, Serial No. 757,796, and in Denmark February 5, 1924.

This invention relates to balls for playing various kinds of games where kicking is not included or allowed, and which balls consist of an inner inflatable bladder or ball to be 5 blown up and an outer cover.

The object of the present invention is an improved arrangement of the insertion of the inner elastic bladder as well as safe-keeping and pinching together the hose- 10 valve leading to same.

In order that the invention may be more clearly understood, reference is made to the accompanying drawings.

Fig. 1 shows an upper view of the ball. 15 Fig. 2 shows a piece of the bladder with the hose-valve doubled up.

According to my invention I produce an outer cover of a strong but soft stuff such as cloth and the like. The cover consists of 20 a number, preferably eight, of identical pieces of the said stuff, *a*, sewed together in such a way that the pointed termination of the pieces shapes the two poles *b* of the ball. One of these eight end-pieces *c* is left free, 25 the seams terminating about 3 inches from the pole, thus producing a closing-flap *c*. Beneath this closing-flap is a stop-flap *e* consisting of a piece of the same stuff sewn to the two side-pieces of the cover and terminating an inch below the free edges of the 30 closing-flap thus leaving free entrance *h* for insertion of the inside bladder. In the middle of this inner stop-flap is a hole *g*, through which the hose-valve *d* from the 35 bladder is run. For fastening the closing-flap hooks and eyes *i* and *j* are sewn respectively below the point edge of the closing-flap and the stop-flap's termination by the pole.

40 The ball is made ready for use in the following way:

The bladder rolled up lengthwise is inserted through the opening *h* inside the outer cover, whereupon the hose-valve *d* is put through the hole *g* in the stop-flap. Air is 45 blown into the bladder. The bladder is closed by merely doubling up the hose and in this position squeezed between the stop-flap *e* and the closing-flap *c*, where the pressure from the bladder will keep up this position and prevent outflow of the air. The projecting end of the hose *d* is once more doubled up between the flaps, and the closing-flap is hooked together with the stop-flap by the pole. 50

55 What I claim as my invention is:—

A ball, comprising, in combination, an inner bladder having a flexible tubular inlet stem, a casing formed of a plurality of strips of material, each strip tapering to a point at 60 each end thereof, said strips being stitched together along their edges to form an approximately spherical casing, the stitching of one of said strips being omitted at both sides thereof from one end to a predetermined point in the length of the strip thereby to provide an approximately triangular flap movable for opening and closing the casing, an inner stop flap stitched to the strips adjacent to said closing flap, said stop 65 flap being provided with an opening for the passage of said tubular stem to a position between the flaps whereby upon inflation of the bladder the tubular stem is confined between said flaps thereby to prevent escape 70 of air from the bladder, and means for securing the closing flap in closed position. 75

In testimony whereof I have signed my name to this specification.

NIELS PETER THYGESEN.
